INVENTOR

UNITED STATES PATENT OFFICE.

JAMES IRONS, OF PHILADELPHIA, PENNSYLVANIA.

DESIGN FOR SHOW-CASES.

Specification forming part of Design No. 7,062, dated December 16, 1873; application filed September 22, 1873.
[Term of Patent 7 years.]

To all whom it may concern:

Be it known that I, JAMES IRONS, of Philadelphia, in the county of Philadelphia and State of Pennsylvania, have invented a certain new and useful Design for Show-Cases; and I do hereby declare the following to be a full, clear, and exact description of the invention, such as will enable others skilled in the art to which it pertains to make and use it, reference being had to the accompanying drawings, which form part of this specification.

The design consists of a show-case for counters and tables, having a curved or convex front, A, and curved or convex sides or ends

B, substantially as shown in the accompanying drawing, which represents a perspective view of the design.

I claim—

The design for a show-case, having curved or convex ends and front, as shown and described.

In testimony that I claim the foregoing I have hereunto set my hand this 18th day of September, 1873.

JAMES IRONS.
